UNITED STATES PATENT OFFICE

158,143

HOLE CUTTER FOR COIN COLLECTION
CARDS OR SIMILAR ARTICLE

Forrest I. Sollenberger, Arlington, Va.

Application July 8, 1949, Serial No. 3,784

Term of patent 14 years

(Cl. D74—1)

To all whom it may concern:

Be it known that I, Forrest I. Sollenberger, a citizen of the United States, residing at Arlington, in the county of Arlington and State of Virginia, have invented a new, original, and ornamental Design for a Hole Cutter for Coin Collection Cards or Similar Article, of which the following is a specification, reference being had to the accompanying drawing, forming part thereof.

Fig. 1 is a top plan view of a hole cutter for coin collection cards or similar article, showing my new design;

Fig. 2 is a side elevational view;

Fig. 3 is a sectional view taken on the line 3—3 of Fig. 2;

Fig. 4 is an end elevational view; and

Fig. 5 is a slightly enlarged section taken on the line 5—5 of Fig. 1.

The characteristic features of my design reside

in the portions shown by means of full lines in the drawing.

I claim:

The ornamental design for a hole cutter for coin collection cards or similar article, as shown and described.

FORREST I. SOLLENBERGER.
